UNITED STATES PATENT OFFICE.

JOHN LORRAINE AND RALPH S. HAUGH, OF MEDICINE HAT, ALBERTA, CANADA.

ROTARY TOOTHBRUSH.

Application filed August 1, 1922. Serial No. 578,879.

To all whom it may concern:

Be it known that JOHN LORRAINE and RALPH S. HAUGH, citizens of the Dominion of Canada, residing at Medicine Hat, in the 5 Province of Alberta and Dominion of Canada, have invented new and useful Improvements in Rotary Toothbrushes, of which the following is a specification.

The object of the invention is to provide 10 a simple and efficient construction of rotary tooth brush whereby the proper movement of the bristles upon the teeth, namely from end to end thereof as distinguished from a cross-wise or lateral movement, may be effected with convenience and facility to the 15 operator and with a rapidity insuring efficiency; and with this object in view the invention consists in a construction and combination of parts of which a preferred embodiment is shown in the accompanying 20 drawings, wherein:—

Figure 1 is a side view, and

Figure 2 is a longitudinal sectional view 25 of a brush constructed in accordance with the invention.

The device consists essentially of a tubular casing 11 in which is revolvably mounted a tubular holder 10, the holder having a swivel connection with the casing as by being provided with a peripheral web 12 fitted in a bearing in the casing which is closed by the removable cap 13 and which preferably carries anti-frictional bearing elements 14, the holder being provided at its outer end with a 30 socket 15 for the reception of the stem 16 of a brush head 17, together with means for imparting a rotary motion to the stem. In the construction illustrated said means include a plunger 18 slidably fitted in the casing and 35 preferably within the tubular holder which is provided with keys 19 engaging spiral thread grooves 20 in the plunger so that when the latter is moved longitudinally with 40 relation to the casing it serves to communicate a rotary motion to the holder, the rotation of the plunger being prevented by hav-

ing a shank 21 terminally provided with a pressure button 22 and having a key or web 23 engaging a suitable seat 24 in the end of the casing. The advance movement 50 of the plunger is yieldingly resisted by a spring 25 which serves to return the same to its normal position when pressure upon the button is released.

Therefore by alternately pressing and releasing the button 22, the casing being held in the end and preferably being exteriorly milled at 26 to afford a satisfactory grip, the plunger communicates rotary motion alternately in opposite directions to the holder 60 to which the stem of the brush head is attached, the return of the plunger after each forward impulse being effected as above noted by the spring 25, so that an alternate rotation in opposite directions of the brush 65 head is effected at a rapidity depending upon the preference of the operator.

Having described the invention, what is claimed as new and useful is:—

A rotary tooth brush structure comprising 70 a relatively short cylindrical casing adapted to serve as a handle grip, a tube journaled in the casing, said tube being relatively long and having an end portion extending for a considerable distance beyond 75 the end of the casing, a cylindrical brush fixed to the distal end of the tube and having all of its bristles exposed, means for retaining the tube against longitudinal movement with relation to the casing, a plunger 80 slidably mounted in the tube and completely housed therein, there being pin and spiral groove connection between the plunger and the tube, a handle carried by the plunger and normally disposed beyond the end of the 85 casing and a coil spring housed in the tube and interposed between the plunger and the brush.

In testimony whereof they affix their signatures.

JOHN LORRAINE.
RALPH S. HAUGH.
